TRAIN OPERATING SYSTEM

Archibald G. Shaver, Chicago, Ill.

Application July 13, 1929, Serial No. 378,000

39 Claims. (Cl. 246—8)

This invention relates to train operating systems and more particularly to a system in which there may be communication direct between the dispatchers and trains and between the conductors and enginemen of trains, for the transmission of orders and information; the dispatchers may operate signals at selected points, as at passing tracks, for the control of train movements; and switches may be operated to divert trains from main lines to passing tracks and return automatically to normal position, etc.

It is now the practice of railway train dispatchers to transmit orders for a train to an operator out along the railroad at a point in advance of the train. The operator stops the train, or causes it to slow down, that it may be given the orders which he has for it. Such orders often pertain to a train diverting to a passing track to let another train pass. When the train reaches the passing track which it is to enter, it stops while an employee operates the track switch leading to the siding; the train enters the siding and, on clearing the main track, again stops while an employee returns the track switch to its normal or main track position.

The object of this invention is to provide a train operating system such that the dispatcher may give orders direct to the crew of the train, whether the train be moving or standing still, thus making wayside operators unnecessary for transmitting orders and eliminating stops and slow-downs of the train to pick up orders. Also, as a check against the misunderstanding and non-fulfillment of the orders on the part of the crew of the train, the dispatcher may control the signals at passing tracks to insure stopping of trains in case the orders are misunderstood or overlooked. After receiving the orders from the dispatcher, the conductor and engineman may communicate with each other in regard to carrying out the said orders. Further, means are provided such that when the train approaches a passing siding, the track switch may be operated for the train to enter the siding without the train having to stop for that purpose; and when the train has cleared the fouling point of the siding with the main line the track switch will automatically return to the normal position. Therefore, with the switch reversing as the train approaches it and returning to normal after the train has passed over it, stops of the train, such as now must be made under present practices, are avoided.

55 Additional objects are :

To provide a novel signaling means for calling attendants to receive a communication.

To provide amplification at the transmitter of the signals used in communication;

To provide an intermediate circuit for communication wherein certain transpositions of conductors are made to minimize inductive noise disturbances;

To provide means admitting of communication between the train and the dispatcher continuously as the train proceeds from the main line onto the siding, and while on the siding;

To provide a track switch connecting and operating means which permits of trains operating through the switch trailing without being damaged or damaging the points of the switch;

To provide a switch locking means which locks the track switch for trains passing thereover in the facing direction, but which does not lock the track switch for trains passing thereover in the trailing direction.

To provide an intermediate circuit for communication which includes both the main line and the siding;

To provide a switch operating means including a combination of power mechanism and switch stand control, the operation of either one of which is optional.

To provide power operated switch control means including a device which will lock the switch automatically in either the normal or reverse position through the force of a spring, but which requires power to be unlocked;

To provide a power operated track switch which may be controlled from either the roadside or from the train;

Other objects and advantages will appear as the description progresses.

In describing one embodiment of the invention in detail, reference will be made to the accompanying drawings in which:—

Fig. 1 illustrates diagrammatically a stretch of main track (part of an equipped railroad) with a siding leading therefrom, and means for carrying on communication between a train and a roadside station and between the head end and the rear end of a train.

Fig. 2 is a diagram of the transmitting and receiving equipment on the train.

Fig. 3 illustrates diagrammatically a portion of the same stretch of railway track as Fig. 1, but upon which are indicated the circuits and equipment concerned in the operation of the track switch.

Fig. 4 is a diagrammatic plan view of the me- 55

chanical features for operating and protecting the switch.

Fig. 5 is a section and diagrammatic partial elevation of the directional locking arrangement, 5 on line K—K of Fig. 4.

Fig. 6 is a cross section of part of the power mechanism for the switch.

Fig. 7 is a cross section of the locking device for the switch.

10 Fig. 8 is a diagrammatic view showing a part of a control rod for locking the switch.

Fig. 9 is a graphical view of the operation of the contacts in the circuit controller.

15 Fig. 10 is a diagrammatic view of the normal circuits, signaling means, communication transmitting means and communication receiving means with one stage of amplification for the transmitter, and two stages of amplification for the receiver, for the train communication station.

20 Fig. 11 is a diagrammatic view of the normal circuits, signaling means, communication transmitting means and communication receiving means, with one stage of amplification for the transmitter and two stages of amplification for 25 the receiver, for the roadside communicating station.

Fig. 12 is a diagrammatic illustration of a 30 slightly different arrangement of communicating circuits at a passing siding from that shown in Fig. 1.

Communicating system.—This is of the same general character and represents further developments and improvements over the systems illustrated and described in my pending applications 35 Serial #227,932, filed October 22nd, 1927, Serial No. 304,483, filed September 7th, 1928, and Serial No. 306,905, filed September 19th, 1928. As is the case in the applications referred to, this invention provides for carrying on communication between 40 the front end and the rear end of a train, and between either or both of the train stations and a wayside station. Normally the apparatus is set up to function to permit communication between the head and the rear end of the train to be carried on at any time or at all times. Generally the 45 wayside station is not in communicative relationship with the train unless certain connecting apparatus is operated, including a transformer, as will be specifically described later; however, means are provided by which the train may automatically connect itself with a wayside station; further, a permanent connection may be made from the wayside station with an intermediate circuit for a train station in a prescribed territory.

55 The several principal features comprised in this train communication system are: transmitting and receiving communicating sets on the train (usually in case of short trains only one set will be required on the train); an intermediate circuit which is in communicative relationship with the train carried sets and adapted to be placed in communicative relationship with the wayside station; a wayside station and circuit including a transmitting and receiving communicating set; 60 and remote control or selective apparatus which makes it possible for the dispatcher or an attendant in the wayside station to connect the wayside circuit with the intermediate circuit and thus with the train in said intermediate circuit.

65 This system of communication will be more particularly described in its use for operating railway trains, whereby the conductor and engineman of the train may communicate with each other, and the dispatcher in charge of the district 70 may communicate with either or both of them.

In Fig. 1, SW is a track switch which connects the siding with the main line. A, B, C, D, E, F, G, H, I, etc., are sections of track in said stretch. B, D, F, G and H are track section circuits with a relay therein in each case normally energized, 5 as indicated by relays TB, TD, TF, TG and TH respectively. S₂ and S₃ are signals governing train movements over the track switch SW along the main line. S₁ and S₄ are signals governing train movements over the switch between the 10 main line and the siding. YB, YD, YF, 11 and 18 are selector relays controlled by the dispatcher in his selective system through the conductors D₁ and D₂ from the dispatcher's station. WB, WD, 15 WF and WG are transformers provided for connecting the intermediate circuit with the dispatcher's wayside circuit, the first three being controlled respectively by the selector relays YB, YD and YF; and WG being controlled by track relay TH. The selector relays 11 and 18 are for 20 the control of signals as will be more fully explained later in Fig. 3. T and RS and SOS are the transmitting and receiving communicating set and the selective operating set respectively in the dispatcher's office or wayside station. SM is a 25 power mechanism for operating the track switch SW; SL is a power mechanism for operating lock plunger LP for locking and unlocking the track switch. 148 is a switch stand for also operating the switch SW by manual means. FPL is a fac- 30 ing point lock for locking the points of the switch, as the train approaches same in a direction facing the switch, shown in detail in Figs. 4, 5 and 8. SB is a spring buffer means in the control rod connecting the switch SW with the mechanism SM, 35 and may be any one of several well known makes, as the mechanical switchman manufactured by Pettibone-Mulliken Co. 111 indicates a train in the intermediate section C. Conductors 100, 103, 105, 107, 109, 111 and 116 are located on the 40 trackway, usually on the ties in the center of the track between the two track rails X and Y. J, J, J, etc., indicate insulated joints which fix the limits of track circuits concerned in the proper operation of this train operating system. TBB, TBD, 45 TBF and TBG are batteries for track circuits, B, D, F and G respectively.

In Fig. 2, T and RC represent transmitting and receiving equipment for the train carried communicating station. Connected with it is a loop 50 or coil 115 representing the inductor. Where the head end and the rear end of the train are equipped, both such stations will be of the type indicated in Fig. 2. The inductor 115, which is located on the train, is normally in inductive relationship with the center of the track conductor, which forms a part of the intermediate circuit. Instead of a coil of several turns, the inductor 55 115 may be a single conductor loop. A type of transmitting and receiving set for a train is illustrated in detail in Fig. 10.

60 Paralleling the stretch of track equipped for this system of communication is a selective and communicating circuit, usually referred to as the dispatcher's telephone line, which is in reality a 65 part of the wayside station equipment already referred to.

That this system of communication may properly meet railway requirements, the arrangement should be such that there will be a minimum of interference with communication between the head end and rear end of a train, and communication between the dispatcher and the train whenever he considers it necessary.

60 In general in operating trains over a track dis- 75

- strict it is necessary for the conductor to give instructions to the engineman. It is also necessary for the engineman to give information to the conductor regarding the conduct of the train, 5 conditions ahead of the train, etc. It is also necessary for the dispatcher to give orders to the trains, as when it is desired that one train take a siding to allow another train to pass, and the like.
- 10 In order to give the flexibility desired and provide an efficient operating system, a communicating zone or circuit arrangement is created, which in reality travels with the train. To provide this traveling zone, a series of intermediate circuits 15 are arranged such that a moving train passes successively from the influence of one intermediate circuit to the next, maintaining itself continuously within a communicating zone for both rear end to head end and train to roadside communication.

Generally speaking, for train communication, and especially telephone communication, amplification is necessary for either transmitted or received signals. Amplification of signals in both 25 the sending and receiving equipment are desirable, especially where inductive disturbances are likely to interfere with audibility.

Intermediate circuits.—The style and length of the intermediate circuit is governed by the 30 density of traffic and the physical and electrical conditions existing in the immediate vicinity of the stretch of equipped track.

The communicating zones, or intermediate circuits, may be shorter for a very busy railway 35 than for one just moderately busy. The type of the intermediate circuit is largely determined by the amount of inductive interference there may be adjacent to the railroad which would hinder proper communication. The intermediate circuit referred to in Fig. 1, about to be described, 40 is one which takes into account both density of traffic and inductive interferences. For ease in describing this system, the stretch of equipped track is divided into a series of sections, A, B, C, D, E, etc.

Comprising an intermediate circuit is a conductor carried on the track, usually in the center of the track, a transformer and a conductor carried on a pole line, connected with the conductor on the track. The pole line conductor is usually referred to as the return part of the circuit. Instead of a conductor on a pole line, a conductor may be carried along the trackside in conduit, or the track rails may be used as the return 45 part of the circuit, or in the case of two-tracks one conductor may be in the center of one track and the other in the center of the other track (see Fig. 12). The transformer is only necessary for communication between the train and wayside. Normally the circuits and apparatus are as indicated in Fig. 1. Where the track rails are used as the return part of the circuit, the rail joints should be bonded. If the track rails already are bonded, due to their use in track circuits, the insulated joints limiting the track circuit sections should be bridged by resistances or by condensers. Either one rail or both rails may be used in the return part of the circuit. In any case, the general arrangement would be similar to that shown in applicant's co-pending application, Serial No. 227,932.

A typical intermediate circuit is that for section C, which includes conductor 103, contact 104 normally closed, conductor 105, transposition TSC, conductor 106, transformer WD, contact

106, conductor 103, and transposition TSC. An adjacent intermediate circuit as that for section E comprises: Conductor 107, contact 108 normally closed, conductor 109, transposition TSE, conductor 109, transformer WF, contact 110 normally closed, conductor 107 and transposition TSE. It will be noted that although these intermediate circuits are adjacent, each is electrically separate and distinct from the other. When a train passes from intermediate circuit C to intermediate circuit E, it must travel through track section D. While the train is in track section D, relay TD is de-energized so that contacts 106 and 108 are closed on their back points. This throws the intermediate circuit C and E together 15 into one combined circuit which then comprises: conductor 103, contact 104 normally closed, conductor 105, transposition TSC, conductor 105, back contact 108 closed, conductor 109, transposition TSE, conductor 109, transformer WF, front contact 110 normally closed, conductor 107, transposition TSE, conductor 107, contact 106 closed on its back point, conductor 103, transposition TSC. In this combination of the two intermediate circuits another transposition of 25 the conductors takes place in that the relay TD being de-energized, the track conductor 105 is connected to line conductor 109, and track conductor 107 is connected to line conductor 103.

In some installations the transposition which 30 occurs, when the track relay contacts are in their abnormal state, is sufficient to counteract any detrimental inductive effects there may be, when two adjacent intermediate circuits are temporarily combined into one circuit.

When a train enters a passing siding an arrangement is desirable that communication for intra-train purposes and communication with the dispatcher may be maintained.

As shown in Fig. 1, there is a separate and distinct intermediate circuit for the siding, which 40 will be referred to as intermediate circuit H, and only one half of which is shown in the illustration. Normally this intermediate circuit H comprises: conductor 116, front contact 13 normally closed, transformer WG, front contact 14 normally closed, and line conductor 118. The other half of this circuit, corresponding with the other half of the siding, also not shown, is identical with that quoted.

For the main line including the track section I of Fig. 1, there is another separate and distinct intermediate circuit which comprises: track conductor 111, front contact 112 normally closed, and line conductor 113. The other half of this circuit 55 which is not shown is identical with that quoted, except the unshown part contains a transformer identical in its connection as that referred to for intermediate circuits C and E.

For a train passing through section F, track relay TF is de-energized, in turn de-energizing repeater relay FR, thus causing contacts 110 and 112 to be made on their back points. During the time that the train is within section F, contacts 110 and 112 continue to be made on their back 60 points so that the two adjacent intermediate circuits, that for E and that for I, are connected together, conductor 113 being connected to conductor 109 through the back contact 112, and conductor 111 being connected to conductor 107 through the back contact 110. When the train 65 goes into the siding, relay TG is de-energized so that contacts 13 and 14 are made on their back points, thus connecting conductor 116 to transformer WF, and through conductor 114 to con- 70

ductor 107, and also connecting track conductor 109 through back contact 74 with line conductor 118. Therefore, for the period that the train is within the track sections F and G, the three intermediate circuits for sections H, I and E, are connected together, substantially in parallel, and communication facilities are maintained as the train proceeds. After the train has cleared section F and while it is still in section G, intermediate circuits E and H are connected together. When the train passes out of section G into section H, it is wholly within the zone of intermediate circuit H for communicating purposes. The foregoing explanation of the intermediate circuit arrangement shows how a train is always within an intermediate circuit which is in continuous communicative relationship with the inductors and related parts on the train, creating a zone of communication for the train which travels with the train. This arrangement is, in effect, what may arbitrarily be considered a traveling intermediate circuit or a traveling communication zone.

In the type of intermediate circuit illustrated in Fig. 12, the normal condition of the circuits and apparatus for communication purposes is as indicated. There is shown the complete intermediate circuit for the stretch of track embracing the siding, section H₁, and the main line, section I₁, and parts of two intermediate circuits in the main line section E₁ and L₁.

Here the conductor is carried down the center of the track for the passing siding and returned in the center of the track for the main line. X and Y are the track rails. T_{F1} and T_{K1} are normally de-energized track relays. F_X and K_X are insulated sections of track rails long enough so that when a train passes over them they are always occupied by a pair of wheels. W_{F1} and W_{K1} are transformers for connection with the wayside station circuits. T_{B_{F1}} and T_{B_{K1}} are track batteries for energizing track relays T_{F1} and T_{K1} respectively. TSH is a transposition of the center of track conductors of the siding and the main line. J₁, J₂, etc., are insulated track joints. 410 is a high voltage power line or other source of inductive effect, in the immediate vicinity of siding H₁. Y_{F1} is a selector relay. D₁ and D₂ are conductors of the dispatcher's telephone and selective system. 400, 403, 405 and 407 are conductors of intermediate circuits located on the track, preferably in the center between the train rails. SW₁—SW₂ are the track switches leading to the siding. E₁, F₁, H₁, I₁, K₁ and L₁ are sections of track of which F₁ and K₁ are for operating track relays.

For sections E₁ and L₁ part of the intermediate circuit is on the trackway, preferably in the center between the track rails, and part is removed therefrom to a pole line or a conduit on the right of way. These circuits are in general arranged the same as shown in Fig. 1 and described for typical section C, the only difference being they are controlled by normally de-energized track relays.

The partial circuit shown for section E₁ comprises, conductor 400 in the center of the track, transformer W_{F1}, back contact 401, normally closed, and conductor 402. The balance of the circuit is identical with that part shown for section L₁ which comprises conductor 407, back contact 408 normally closed, and conductor 409. Fixed transpositions will also be made in these circuits, like TSC of Fig. 1, when required.

In Fig. 12 the intermediate circuit for sections

H₁, siding, and I₁, main line, comprises: conductor 403 in the center of the siding, back contact 404 normally closed, conductor 405 in the center of the main line, transposition TSH, conductor 405 in the center of the siding, back contact 406 normally closed, transformer W_{K1}, conductor 403 in the center of the main line and transposition TSH.

With a train in section F₁, relay T_{F1} is energized closing contacts 404 and 401 on their front points and connecting conductor 402 with conductor 405 and conductor 400 with conductor 403. In this way the conductors of adjacent circuits are connected together in transposed relationship to form a single enlarged intermediate circuit adapted to cooperate with the train while the train is passing from one section to another.

With the train in section K₁ relay T_{K1} is energized, closing contacts 408 and 406 on their front points and connecting conductor 405 with conductor 407 and conductor 403 with conductor 409. It will be observed that in this case also the conductors of the adjacent circuits are connected in transposed relationship to form a single large intermediate circuit in which the inductive disturbances are reduced to a minimum.

Transpositions in intermediate circuits, as TSH, are desirable when inductive disturbances are present of the character which will affect the operation of the communicating system. Then they are made of a frequency and at locations to best meet the condition existing in the locality.

In Fig. 12 assume a high voltage power line, as conductor 410 adjacent the railroad track, which produces inductive effects in the intermediate circuit for sections H₁ and I₁, transpositions would be made between the conductors 403 and 405 as shown at TSH, of the number and at locations to greatly minimize, if not entirely eliminate, the inductive disturbance. Assume but one transposition will be necessary in the case of this intermediate circuit, it will be located so that any inductive disturbance in one loop will balance the inductive disturbance in the other loop, and since they are in opposite directions, one will destroy the other. For example, if the exposure of conductor 405 to power line 410 is the same as the exposure of conductor 403 to the power line, the induction in each is equal, and since this inductive effect is in opposite directions in the circuit, as illustrated by arrows 411 and 412, it will destroy itself.

Transformers W_{F1} and W_{K1} may be connected in one of several ways to the wayside station conductors D₁ and D₂, or the dispatcher's system. Usually transformer W_{F1} will be connected as shown through the operation of the selective system; but transformer W_{K1} will be preferably either permanently connected to the wayside circuit, as shown, or automatically connected due to the presence of the train on the siding or on the main line between switches SW₁, in order to give trains in this intermediate circuit the privilege of initiating communication with the dispatcher. This intermediate circuit H₁—I₁ may also be selectively connected to the dispatcher's line if desired. In Fig. 1 transformer W_G is arranged to be automatically connected to the wayside system, conductors D₁ and D₂, by the presence of a train in section H.

The intermediate circuit for section H₁—I₁ of Fig. 12 has an advantage in that both sides of the intermediate circuit are available for communication purposes; and it would be adaptable for use on a double track railroad. Expense of

installation and maintenance would then be proportionally decreased. Also, communication could be carried on between a train on the main line and one on the siding, without disturbing the dispatcher, or providing connections through a transformer.

Referring again to Fig. 1, assume intermediate circuits A, C and E and train 117 of such length that the train at one time occupies all three of 10 said intermediate circuits including the track section circuits B and D. Relays TB and TD being de-energized, their contacts are made on their back points resulting in intermediate circuits for 15 A, C and E being combined in one circuit for such time, such combined circuit comprising,— conductor 100, back contact 104, conductor 105, transposition TSC, conductor 106, back contact 108, conductor 109, transposition TSE, conductor 109, transformer WF, front contact 110, conductor 107, transposition TSE, conductor 107, back contact 106, conductor 103, transposition 20 TSC, conductor 103 and back contact 101 to conductor 102. The part of the intermediate circuit A, not shown, which is identical with the 25 left hand section of intermediate circuit C, completes the combined circuit; and transformer WF is adapted for the dispatcher to connect his telephone line, conductors D1 and D2, with such combined circuit when he desires to communicate 30 with the train. Two trains running close together might form such combined circuit, one train being within track section circuit B and the other in track section circuit D, in which case the trains may communicate with each other.

The wayside station and system.—Located in the wayside station is a transmitting and receiving set T and RS, and a selector operating set SOS (Fig. 1). Each of these sets when in use is connected directly to conductors D1 and D2 which 40 extend along the railroad throughout the stretch of equipped track. Connected with the conductors D1 and D2 are selector relays YB, YD, YF, 11 and 18. The first three are for the purpose of connecting the dispatcher's line, conductors D1 and D2, directly with the corresponding 45 intermediate circuits, A, C and E, through the medium of transformer WB, WD and WF respectively. Selector relays 11 and 18 are for the purpose of operating the signals governing train 50 movements over the switches as will be later explained. Selector relay YB when operated closes contacts 122 and 125, thus connecting transformer WB with conductors D1 and D2 through conductors 121, 123, 124 and 126 respectively. Selector 55 relay YD when operated closes contacts 130 and 133 thus connecting transformer WD and conductors D1 and D2 through conductors 129 and 131 and 132 and 134.

Transformer WF has three coils, one primary, 60 and two secondary; one secondary is the medium for connecting intermediate circuit E, and the other secondary the medium for connecting intermediate circuit H to the dispatcher's line, conductors D1 and D2. When selector relay YF is 65 operated, contacts 136 and 139 are closed, connecting the transformer primary coil conductor 135 to conductor 137, and conductor 138 to conductor 140.

Selector relay YB is connected to dispatcher's 70 line, conductors D1 and D2, by conductor 119 and conductor 120 respectively. Selector relay YD is connected to dispatcher's line, conductors D1 and D2, by conductors 127 and 128 respectively. Selector relay YF is connected to dispatcher's 75 line, conductors D1 and D2 by conductors 153

and 154 respectively; selector relays 11 and 18 are connected to dispatcher's line, conductors D1 and D2, by conductors 145 and 146 respectively. The circuit for repeater relay FR includes contact 12 normally closed and battery 155.

The selector operating system SOS and the selectors responsive thereto may be of any one of the several well known systems in commercial use as that of the Western Electric, the Gill, or the Sandwich. In these systems a key or switch in 10 the dispatcher's office is adapted to send out a code of electrical impulses, there being a different code for each selector. When the dispatcher wishes to operate a particular selector, he connects the code key corresponding to that selector 15 to the conductors D1 and D2. When he operates this key a code of impulses is sent out over the conductors D1 and D2 and said selector, being energized by these impulses, responds thereto. All other selectors, not being responsive to said impulses, do not function.

The track circuits for section B, D, F, G, etc. of Fig. 1, are of the usual type where the track rails are part of the circuit and a battery located at one end of the section is connected to the track 25 rails, and the relay at the other end of the section is also connected to the track rails. These track relays as shown in Fig. 1 are normally energized.

When the train is in section H relay TH is de-energized, closing back contacts 75 and 76, connecting conductors 147 with 152 and 149 with 151 respectively, so that transformer WG is bridged across the dispatcher's line, conductors D1 and D2, and in this manner the intermediate circuit H is automatically connected to the dispatcher's line.

Wayside station transmitting and receiving set T and RS.—In Fig. 11 are the details of the transmitting and receiving set in the roadside communication station, which may also be considered as the transmitting and receiving set in the dispatcher's office.

O2 is a generator for signaling purposes, of the same frequency of electric current as generator O1 in Fig. 10 to give a high pitch note, but of interrupted current to be distinguishable from the signal resulting from the operation of O1. HS2—HS4 is a double contact hand switch of the push key type for operating the signaling or calling circuits pertaining to generator O2. Switch arms HS2 and HS4 are here shown as operating 50 together. SA2 is a switch device for controlling various circuits relating to the transmitting and receiving means, normally held in the position shown by spring 376. T2 is a transmitter. TB2 is a source of energy in the transmitting circuit. 55 W2 is a transformer connecting the transmitter circuit with the transmitting amplifying circuit. V2 is a transmitting amplifying tube. A2 and BL2 are sources of energy respectively for filament and plate circuits of tube V2. G2 is the battery 60 for grid of V2.

D1 and D2 are the conductors for dispatcher's telephone and selective system, or for the roadside communicating station along the track. 192 and 156 are conductors connecting the transmitting 65 and receiving means of the wayside station with the roadside conductors D1 and D2.

W4 is a transformer connecting the amplifying transmitter circuit to the circuit leading to conductors D1 and D2.

W6 is a transformer connecting the receiving circuits in the wayside station with the wayside conductors D1 and D2.

U2 and U4 are amplifying tubes for two stages of amplification in the wayside receiving circuit.

A4 and BL4 are sources of energy respectively for the filaments and plate circuits of tubes U2 and U4. G4 and G6 are the C batteries respectively for the grids of U2 and U4. W8 is a transformer connecting the amplifying circuits of tube U2 with the amplifying circuits of tube U4.

LS2 is a signaling receiving means on the order of a loud speaker, a relay or an alarm responsive to the signals sent out from the sources of energy 10 of the train stations; also serving to indicate when generator O2 is operated.

RE2 is a receiver on the order of a loud speaker, or it may be a receiver of the type known as head phones.

15 Q2 and C10 are condensers. Either may be of the adjustable type.

SC2 is a switch on the order of the ordinary telephone receiver hook. Normally it is closed on contact 362 in the circuit for device LS2. If 20 it supports the receiver RE2, then, when this receiver is removed, contact 358 will automatically close.

Connected with switch arm SC2, and operable with it, is switch arm SC4. Normally contact 25 374 is closed to include condenser C10 in the circuit of transformer W6. When this switch arm SC4 is operated to close contact 372, condenser C10 is eliminated from the circuit of transformer W6.

30 Impedance Z2 is in the circuit of transformer W6 when generator O2 is energized in the circuit of conductors D1 and D2, etc. The resistance factor of Z2 is large so that not enough energy passes from generator O2, when the hand switch HS2—HS4 is closed, to transformer W6 to overload the amplifiers. The inductance factor of the circuit which includes impedance Z2 is preferably equivalent to the capacity factor of the circuit including C10. Instead of being an impedance, Z2 may be a resistance. The inductive reactance of the circuit, particularly as regards 35 transformer W6, may be objectionally high. Therefore, the function of condenser C10 is to equalize the inductive reactance of the circuit to the extent that the signal received as an indication of the proper operation of the generator O2 may be distinct and undistorted.

40 RES2 and RES4 are variable resistances controlling the filament currents of tubes V1 and U1 and U3 respectively.

45 50 *Circuit for the wayside station transmitting signaling means.*—The transmitting signaling means is provided for the purpose of calling an attendant on the train by a signal of distinctive character to answer the phone. The circuit (Fig. 11) comprises switch arm HS2, normally open contact 332, conductors 156 and D2, one of the intermediate circuit transformers as WD, depending upon which one is connected by a selector relay, or otherwise, conductors D1, 192 and 334, condenser Q2, generator O2, conductor 308, normally closed contact 306 and conductor 382. When switch HS2 is operated contact 332 closes and the circuit is energized. The condenser Q2 is for the purpose of making the circuit resonant, or nearly so, to the frequency of the generator O2.

55 60 Associated with the transmitting signaling, or calling means, is a means for determining whether the signaling impulses are actually produced by the generator O2. When switch HS2—HS4 is operated contact 378 is opened, disconnecting the primary receiving circuit of transformer W6 from its direct connection with conductor 192, 70 and contacts 332 and 380 are closed placing gen-

erator O2 in circuit with transformer W6 as follows: generator O2, conductor 384, impedance Z2, contact 380, switch arm HS4, conductor 330, contact 328A, conductor 328, transformer primary W6, conductors 326 and 376, condenser C10, contact 374 closed, switch arm SC4, conductor 310, contact 332, switch arm HS2, conductor 382, contact 306 and conductor 308.

75 *Circuits for transmitting communications from the wayside.*—Normally the transmitting circuits of station T and RS are open. When it is desired to transmit a communication (Fig. 11) switch SA2 is operated against the force of spring 376 closing contacts 318, 304A and 336A and opening contacts 328A, 366A and 306.

10 The transmitter circuit comprises transmitter T2, conductor 302, transformer primary W2, battery TB2, contact 304A closed only when switch SA2 is reversed, and conductor 304.

15 The communicating impulses set up in the transmitter circuit are induced through transformer W2, into the transmitting amplifying means, the circuits for which comprise:

20 Grid of tube V2, conductor 370, transformer secondary W2, battery G2, and conductors 312 and 322. The filament circuit of tube V2 includes battery A2, conductor 316, contact 318 closed when switch SA2 is reversed, conductor 320, adjustable resistance RES2, filament of tube V2 and conductors 322 and 312. In the plate 25 circuit of tube V2 are battery BL2, transformer primary W4, and conductor 324.

25 30 The amplified transmitted impulses are induced through transformer W4 into the wayside circuit including conductor 336, contact 336A closed when SA2 is reversed, conductors 386, 192 and D1, the intermediate circuit transformer which may be connected to conductors D1 and D2, conductors D2 and 156 and secondary of transformer W4.

35 40 *Circuits for receiving in the wayside station.*—Normally the receiving circuits of station T and RS are closed as illustrated in Fig. 11. It is considered good practice in this system to open them when communications are being 45 transmitted from the same station. The primary receiving circuit for signaling comprises conductors D1 and 192, contact 378, conductor 330, switch 328A normally closed, conductor 328, transformer primary W6, conductors 326 and 376, condenser C10, contact 314, switch arm SC4, and conductors 310, 156 and D2. Whichever transformer in an intermediate circuit is connected to conductors D1 and D2, completes this 50 primary receiving circuit. The condenser C10 is for the purpose of making the calling primary receiving circuit resonant, or nearly so, to the 55 frequency of the signaling current.

55 60 The primary receiving circuit for communications in the wayside station is the same as the primary receiving circuit for signaling, just described, except that part of the circuit connecting between conductors 326 and 310 includes contact 372 closed, instead of contact 374, and condenser C10 is eliminated from the circuit.

65 70 At transformer W6 the received signaling and communicating impulses are carried to the receiver amplifier the circuits for which comprise:

75 80 For the grid of tube U2, conductor 346, transformer secondary W6, battery G4 and conductor 338 and 340 to filament of U2.

85 The filaments of tubes U2 and U4 are connected in parallel by conductors 342 and 344 and to a source of energy A4 by the circuit including adjustable resistance RES4, conductor 75

366, contact 366A normally closed, and conductor 368.

The plate circuit of tube U2 includes conductor 348, transformer primary W8, conductor 358, 5 and battery BL4.

The grid circuit of tube U4 includes conductor 352, transformer secondary W8, battery G6 and conductor 342.

For the amplified received call signals the plate 10 circuit of tube U4 includes battery BL4, conductors 350 and 360, signaling means LS2, contact 362 normally closed, switch SC2, and conductor 364.

For the amplified received communication 15 signals, the plate circuit of tube U4 includes battery BL4, conductors 350 and 354, receiver RE2, conductor 356, contact 358 closed, switch SC2, and conductor 364.

Train carried stations.—Fig. 2 shows a transmitting and receiving communication set T and RC on the train. This is connected to a loop or coil comprising inductor 115 for both transmitting and receiving. Inductor 115 is located on the train to be inductively associated with that conductor of the intermediate circuit which is located on the track; for example, with a train in section C, Fig. 1, inductor 115 is located to be within the proximity of track conductor 103 or 105 so that any transmitting current influence in inductor 25 115 will be inductively received in conductor 103 or 105, and thus into the intermediate circuit. Conversely any current influence in the intermediate circuit will be transmitted from conductor 103 or 105 to inductor 115 and thus be received in the 30 receiver on the train. Instead of a coil of several turns the inductor 115 may be a single conductor loop.

When there are two communicating stations on the train, both will be the same as the one described, and each will be in the same relationship with the track conductor of the intermediate 40 circuit.

Train transmitting and receiving set T and RC.—In Fig. 10 is shown the details of the transmitting and receiving set in the train station, or in the train stations when both ends of the train are equipped.

O1 is a generator for signaling purposes preferably of a prescribed electric current output of a frequency giving a high pitch note. HS1—HS3 is 50 a double contact hand switch, of the push key type for operating the signaling or calling circuits pertaining to generator O1. Switch arms HS1—HS3 are here shown as operating together.

I15 is an inductor which is here shown as of the 55 loop or single conductor type. It may also be of a coil type, consisting of several turns of a conductor, or it may be of an electromagnetic type comprising a coil with an iron core.

SA1 is a switch device for controlling the 60 various circuits relating to the transmitting and receiving means. 375 is a spring holding switch SA1 in the normal position. T1 is a transmitter. TB1 is a source of energy in the transmitting circuit. W1 is a transformer connecting the transmitter circuit with the transmitter amplifier. V1 is a vacuum tube, amplifying the transmitted signals. A1 and BL1 are respectively the filament 65 and plate sources of energy for transmitting tube V1. G1 is the C battery for grid of V1. Transformer W3 connects the amplified energy with the circuit of inductor 115.

W5 is a transformer connecting the receiving 70 means with the inductor 115. U1 and U3 are vacuum tubes for two stages of amplification of 75 the received signals. A3 and BL3 are sources of

energy respectively for the filament and plates of the tubes U1 and U3. G3 and G5 are the C batteries respectively for the grids of U1 and U3. W1 is a transformer connecting between stages of amplifier U1 and U3. LS1 may be a loud 5 speaker, or it may be a relay or some other device which is responsive to certain signals as those emanating from generator O1, or from generator O2 of the wayside station. RE1 is a receiving instrument. It may be a loud speaker or it may be 10 of the head type of receiver.

Q1 and C9 are condensers, either may be of the adjustable type.

SC1 is a switch on the order of the ordinary telephone receiver hook. Normally it closes the 15 contact 361 in the circuit for device LS1. If it normally supports receiver RE1, then the removal of this receiver automatically closes contact 357. Connected with switch arm SC1, and operable with it, is switch arm SC3. Normally contact 313 20 is closed to include condenser C9 in the circuit of transformer W5. When this switch arm SC3 is operated to close contact 371, condenser C9 is eliminated from the circuit of transformer W5.

Impedance Z1 is in the circuit of transformer 25 W5 when generator O1 is energized in the circuit of inductor 115. The resistance factor of Z1 is large so that not enough energy passes from generator O1, when the hand switch HS1—HS3 is closed, to transformer W5 to overload the 30 amplifiers. The inductance factor of the circuit which includes impedance Z1 is preferably equivalent to the capacity factor of the circuit including condenser C9. Instead of being an impedance, Z1 may be a resistance. The inductive reactance of the circuit, particularly as regards transformer W5, may be objectionally high. Therefore, the function of condenser C9 is to 35 equalize the inductive reactance of the circuit to the extent that the signal received as an indication of the proper operation of the generator may 40 be distinct and undistorted.

RES1 and RES3 are variable resistances controlling the filament currents of tubes V1 and U1 and U3 respectively.

Circuit for the train transmitting signal means.—This signaling means is provided for the purpose of calling the attendant on the other end of the train, or the dispatcher when he is called, to answer the phone. Its circuit comprises switch arm HS1, contact 331, closed when 50 HS1 is operated, conductor 309, inductor 115, conductor 333, condenser Q1, generator O1, conductor 307 and normally closed contact 305. When switch arm HS1 is operated, contact 331 is closed and the circuit is energized. The condenser Q1 55 is for the purpose of making the circuit resonant, or nearly so, to the frequency of the generators O1 and O2.

Associated with the transmitting signaling or 60 calling means is a means for determining whether the signaling impulses are actually produced by the generator O1. When switch HS1—HS3 is operated, contact 371 is opened, disconnecting the primary receiving circuit of transformer W5 from its direct connection with conductor 333, and 65 contacts 331 and 379 are closed, placing generator O1 in circuit with transformer W5 as follows: generator O1, conductor 383, impedance Z1, contact 379, switch arm HS3, conductor 329, contact 327A, conductor 327, transformer primary 70 W5, conductors 325 and 375, condenser C9, contact 373 closed, switch arm SC3, conductor 309, contact 331, switch arm HS1, contact 305 and conductor 307.

Circuits for transmitting communications from 75

the train.—Normally the transmitting circuits of Fig. 10 are open. When it is desired to transmit a communication from a train station, switch SA_1 is operated against the force of spring 375 , closing contacts 317 , $303A$ and $335A$, and opening contacts $327A$, $365A$ and 305 . The transmitter circuit comprises transmitter T_1 , conductor 301 , transformer primary W_1 , battery TB_1 , contact $303A$ closed only when switch SA_1 is reversed, and conductor 303 .

The communication impulses set up in the transmitter circuit are induced through transformer W_1 into the transmitting amplifying means, the circuits for which comprise:

15 Grid of tube V_1 , conductor 369 , transformer secondary W_1 , battery G_1 , conductors 311 and 321 . The filament circuit of tube V_1 includes battery A_1 , conductor 315 , contact 317 closed when switch SA_1 is reversed, conductor 319 , adjustable resistance RES_1 , filament of tube V_1 and conductors 321 , 311 and 313 . In the plate circuit of tube V_1 are conductor 323 , transformer primary W_3 , and battery BL_1 .

The amplified transmitted impulses are induced through transformer W_3 into the inductor circuit which includes conductor 335 , contact $335A$ closed when SA_1 is reversed, conductors 385 and 333 , inductor 115 , conductor 309 and transformer secondary W_3 .

30 *Circuits for receiving in a train station.*—Normally the receiving circuits of train station T and RC are closed, as illustrated in Fig. 10. It is considered good practice in this system to open them only when communications are being transmitted from the same station. The primary receiving circuit for signaling comprises inductor 115 , conductor 309 , switch arm SC_3 , contact 373 , condenser C_9 , conductors 375 and 325 , transformer primary W_5 , conductor 327 , contact $327A$ normally closed, conductor 329 , switch arm HS_3 , contact 377 and conductor 333 . The condenser C_9 is for the purpose of making the calling primary receiving circuit resonant, or nearly so, to the frequency of the signaling current.

45 The primary receiving circuit for communications in a train station is the same as the primary receiving circuit for signaling, just described, except that part of the circuit connecting between conductor 325 and 309 includes contact 371 closed, instead of contact 373 , and condenser C_9 is eliminated from the circuit.

At transformer W_5 of Fig. 10 the receiving signaling and communicating impulses are carried to the receiver amplifier, the circuits for which 55 comprise:

For the grid of tube U_1 , conductor 345 , transformer secondary W_5 , battery G_3 , and conductors 331 and 339 to filament of U_1 .

The filament of the tubes U_1 and U_3 are connected in parallel by conductors 341 and 343 , and to a source of energy A_3 by a circuit including adjustable resistance RES_3 , conductor 365 , contact $365A$ normally closed, and conductor 367 .

The plate circuit of tube U_1 includes conductor 347 , transformer primary W_1 , conductor 349 and battery BL_3 .

The grid circuit of tube U_3 includes conductor 351 , transformer secondary W_1 , battery G_5 and conductor 341 .

70 For the amplified received call signals, the plate circuit of tube U_3 includes conductor 363 , switch SC_1 , contact 361 closed, signaling receiving means LS_1 , conductors 359 and 349 and battery BL_3 .

75 For the amplified received communication sig-

nals, the plate circuit includes conductor 363 , switch arm SC_1 , contact 357 closed, conductor 355 , receiver RE_1 , conductors 353 and 349 and battery BL_3 .

Switch and signal operating means.—A feature of the general system of train operation which is comprised in this invention is that of means permitting trains to enter and leave passing sidings and diverging routes. The arrangement is such that normally the passing siding switch is set for the movement of trains along the main line. In the case where a train is to take a siding, a circuit controlling device may be operated, controlled either from the roadside, by the dispatcher, or the train, which will operate the track switch for train movements from the main line into the siding. When the track switch starts to operate, the signals governing train movements over the switch on the main line, will be set at stop. When the track switch is operated to the reverse or open position and is properly locked, signals governing train movements to and from the siding will indicate showing that the route is properly set for the train to proceed. Upon the train proceeding from the main line into the siding and clearing the fouling point of the siding with the main line, the track switch will automatically return to the main line position. Since the operating mechanism is joined to the track switch through a spring connection, it is feasible for a train on the siding to come out on the main line regardless of the position of the points of the track switch. Should the track switch be set for the main line and the train come off the siding, the points will be crowded over by the flanges of the wheels of the train against the tension of the spring connection, and the train will proceed without being damaged or without damaging the points of the switch.

When a train passes over a track switch in a direction facing the points, locking means are provided by which automatically the switch is locked in position, so that the points cannot be moved during the time the train is passing over them. This locking means, as will be hereafter shown, is not operative to lock the points of the track switch when the train passes over same trailing.

It is desirable when the train dispatcher gives an order to the train to take a passing siding, 50 that he be able to check the observance of the order by causing the signals at the track switch to be at stop so as to protect trains, one on or about to take a siding and another on the main line, against collision with each other.

In Fig. 3 the various track sections, signals, track relays, power switch mechanism, and the like, are the same features as referred to in Fig. 1, with the same symbols for each. HS is a circuit controlling device located on the roadside in such a position that it may be operated by hand from a passing train, or it may be operated manually by an attendant on the ground, or by the dispatcher from a distance, or it may be operated by contact or inductive means from the train. Normally circuit controlling device HS is held in a non-contacting position by the spring 80 . R_1 is a relay for operating the track switch from the normal to the reverse position. R_2 is a relay for controlling the operation of the track switch from the reverse to the normal position and it operates automatically. M_1 , M_2 and ML are electromagnetic means controlling the operation of the power mechanisms SM and SL .

LC1, LC2, LC3, and LC4 are circuit controllers normally closed and open as shown, and which have the opposite positions during the interval that the lock plunger LP is withdrawn from the control rod 67. 56 and 49 are selector relay contacts controlling signals S2 and S3 respectively, and operated by selector relay 77. 71 is a contact controlled by selector relay 78 in the circuit of signal S4. 58 is a contact operative from the facing point lock connecting means, rod 64, (Fig. 4) being normally closed, but open when the plunger 65 is engaged with the facing point lock FPL and control rod 181. 72, 73, 74, 75 and 76 are identical with similar contacts shown in Fig. 1 for operating the communicating means. Selector relays 77 and 78 are identical with the similarly numbered selector relays shown in Fig. 1.

FLB is the operating feature of the facing point lock FPL which together with connected rod 64 is referred to in detail in Figs. 4 and 5.

TF is a relay for the track circuit section F which includes that portion of the main line in which switch SW is located. TG is the relay for the track circuit section G in the siding between the connection of the siding with the main line and about the clearance point of the siding with the main line.

SCC is a switch circuit controller connected with, to operate with, the switch SW by the rod 198 (Fig. 4). It contains the electrical contacts C1, C2, C3, C4, C5 and C6 which are made and broken as illustrated by Fig. 9.

Circuit for relay R1.—This relay controls the operation of the track switch from the normal or closed position to the reverse or open position, and comprises common wire CC, contact 79 of circuit controlling device HS closed, conductor 1, back contact 2 closed, conductor 3, coil relay R1, conductor 4, contact C1 closed, conductor 5, battery BY, conductor 6 and common conductor CC. As contact C1 opens with the switch points moving from the normal to the reverse position, when about one half or three fifths of the stroke of the track switch is completed, another circuit is provided to by-pass contact C1, which circuit includes conductor 9, contact LC4 closed, conductor 21, and conductor 5. Contact LC4 closes at the moment the lock plunger LP is withdrawn from the control rod 67, as will be hereinafter explained, and remains closed until the lock plunger LP again locks the control rod 67.

Circuit for lock magnet ML.—Lock magnet ML controls the admission of air or fluid into cylinder SL for the withdrawing of lock plunger LP from the control rod 67. The circuit for the lock magnet ML comprises conductor 6, battery BY, conductors 5, 21 and 10, contact 11 normally closed, conductor 12, coil ML, conductor 13, contact C5 closed with the switch in its normal position, conductor 14, contact 15 closed only when relay R1 is energized, and conductors 16, 17 and common CC. When the switch is in the reverse position, contact C5 is open and contact C6 is closed, the circuit then being from conductor 13 via contact C6, conductor 18, contact 19 closed only when relay R2 is energized, and conductors 20, 17 and common CC.

Circuit for lock magnet M1.—This includes conductor 6, battery BY, conductors 5 and 21, contact LC2 closed, conductor 22, contact 23 normally closed, conductor 24, coil magnet M1, conductor 25, contact 26 closed, and conductors 27, 16a and CC.

Circuit for lock magnet M2.—This includes conductor 6, battery BY, conductors 5 and 21, contact LC2 closed, conductor 22, contact 23 normally closed, conductors 24 and 37, coil magnet M2, conductor 38, contact 39 closed, and conductors 40, 17 and CC.

Circuit for relay R2.—This relay controls the operation of the track switch from the reverse to the normal position and operates automatically after the train has passed over the switch, and while the train is in track section G. This circuit includes common conductor CC, contact 28 closed on its back point, conductor 30, contact 31 normally closed on its back point, conductor 32, coil relay R2, conductor 33, contact 34 normally closed, conductor 35, contact C2 closed when the track switch is reversed, conductors 36 and 5, battery BY and conductor 6.

As contact C2 opens before the switch has entirely completed its stroke in moving from reverse to normal position, a bypass circuit for this contact, when open, is provided, which includes conductor 29, contact LC3 which is closed when the track switch is unlocked and conductors 21 and 5.

Circuit for signal S3.—This signal governs train movements over the switch along the main line. Its circuit comprises common conductor CC, contact 41, normally closed, conductor 42, contact LC1 normally closed, conductor 44, contact 45 normally closed, conductor 46, control mechanism signal S3, conductor 47, contact C3 closed when the switch SW is normal, conductor 48, contact 49 normally closed and conductor 49a, leading on through block to battery and common conductor.

Circuit for signal S1.—This signal governs train movements from the main line into the siding. Its circuit comprises common conductor CC, contact 41 normally closed, conductor 42, contact LC1 normally closed, conductor 44, contact 45 normally closed, conductor 46, control mechanism signal S1, conductor 50, contact C4 closed when the switch SW is reversed, conductors 51 and 5, battery BY and conductor 6 to common conductor CC.

Circuit for signal S2.—This signal governs along the main line over the track switch for trailing train movements. Its circuit comprises common conductor CC, contact 52 normally closed, conductors 53 and 54, control mechanism signal S2, conductor 55, circuit controller 56 normally closed, conductor 57, contact 58 normally closed, conductor 59, contact 60 normally closed, and conductor 61 through the block to battery and common conductor CC.

Circuit for signal S4.—This signal governs train movements from the siding to the main line and through the block. Its circuit comprises common conductor CC, contact 52 normally closed, conductors 53 and 69, control mechanism signal S4, conductor 70, contact 71 normally closed, conductor 51, contact 58 normally closed, conductor 59, contact 60 normally closed and conductor 61, through the block to battery and common conductor CC.

Locking device for train movements facing the track switch.—In Fig. 4 X and Y are the track rails, and 190 and 191 the points of switch SW shown in normal position. Bar FLB is the main operating feature of the facing point switch locking and unlocking means, and is connected with rod 64 by rocking shafts 63 and arms 195 and 176; and rod 64 is connected to facing point lock plunger 65. SB is the spring-buffer means.

joining the power mechanism SM to switch points 190 and 191. SCC is a switch circuit controller connected by rod 198 with the switch SW at lug 174. 171 and 150 are the levers of the dual switch stand 148. Rod 172 is for connecting stand 148 with the switch SW. Rod 173 connects lever 150 with the power mechanism SL for unlocking rod 67. 197 is a circuit controller which comprises contacts LC1, LC2, LC3 and 10 LC4, (Fig. 3). 175 are bearings supported on the track ties for holding rocking shafts 63. DN and DS are direction arrows for convenient use in the description.

Since a spring and buffer SB joins the power mechanism SM to the switch points 191 and 190 the points are held against the stock rails Y and X under pressure from the spring for the respective reverse and normal positions of the switch. Because of this fact some railway operating men are apprehensive that with trains passing over the switch facing the points something may happen to cause the points to open under the train, resulting in a derailment. It is to obviate any such occurrence that locking 25 means about to be described are provided.

FLB is a bar on the order of a channel, two or three inches wide, with top normally about level with the top of the rail and free to move up and down with a circular motion against the 30 ball of the rail when engaged by the flange of a passing car wheel. This bar is of such length as to always be engaged by one or more wheels of a passing train.

Fig. 5 is a view through the track along the 35 section line KK. The bar FLB is held in the extreme upright position by springs 196. It is free to move with a rotating motion because of the arms 195. A pin 194 is fastened to the bar FLB, and arms 195 at one end of rocking shafts 63 rotatably connect between the pins 194 and 40 rocking shafts 63. This type of mounting permits the bar FLB to move forward or backward as indicated by positions b and a of arms 195. The other end of the rocking shafts 63 terminates 45 in arms 176 which are pivotally connected to rod 64. The rocking shafts are free to rotate in bearings 175.

Associated with the control rod 181 for the switch is a facing point lock casting 175^a of the 50 usual well known type. In the control rod 181 are two holes or notches, one corresponding to the normal position of the switch, and the other corresponding to the reverse position of the switch. Plunger 65, under certain conditions to be explained, will enter the holes or notches in rod 181, thereby locking the points of the switch against movement. 177 is a fixture rigidly fastened to a tie, through which the lock plunger 65 is free to pass. Rigidly connected to lock 55 plunger 65, but adjustable as to location on said plunger, are collars 178. Also over said plunger 65, but under balanced tension between said collars 178 and said fixture 177, are springs 179. A function of these springs is to normally withhold the lock plunger from the holes or recesses 60 in control rod 181; a further function of these springs 179 is to hold the bar FLB in an upright position with the arms 195 in a central vertical 65 position.

70 The ends of the bar FLB are inclined down slightly for a distance of about one or two feet, so that when struck by the flange of a passing wheel, there will be less shock, and the tendency will be for the bar to move in the direction of 75 the movement of the train.

When a train is moving facing the switch (direction DS) the flanges of the wheels force bar FLB, forward, holding it in a position corresponding to position b of the arms 195, due to the pressure of the flanges on the top of said bar, 5 as long as there are wheels over the bar. When bar FLB is moved as just indicated, the rocking shafts 63 are operated to cause bar 64 to also move to position b, which forces the lock plunger 65 through a hole in control rod 181 corresponding to the position of the switch. The lock plunger is held in such position until the last pair of wheels has passed off bar FLB, after which bar FLB, due to the pressure exerted by springs 179 and 196, returns to its normal position, 15 unlocking control rod 181.

In the case of a train moving over the switch SW trailing the points (direction DN) of said switch, the wheel flanges again contact with bar FLB, forcing it to a position corresponding with 20 the position a of rocker arms 195. This causes the rocking shafts to move, and since rod 64 is connected with the rocking shafts, it must move in a direction corresponding to bar FLB, which movement draws the locking plunger 65 further 25 from the control rod 181, thus leaving same unlocked for such trailing train movement. It is readily seen, therefore, that when a train trails through the switch under conditions where the switch is not properly set for such movement, 30 the flanges of the wheels are free to force the switch points over without damaging same or without damaging the train.

For movements of the train trailing the switch, where the position of the switch does not correspond with the route of the train, after the switch points are forced over by the wheel flanges, said points will return to their normal position, due to the spring tension in device SB; and the buffer action, in device SB also permits such return 40 slowly and without shock and damage to the switch points.

Power operated switch mechanism.—The type of switch mechanism illustrated in Fig. 4 and in detail of Figs. 6, 7 and 8, is intended for operation by air or by some hydraulic medium as oil or a combination of the two. It consists essentially of an operating cylinder SM and a locking cylinder SL.

65 68 is the head rod connection for the switch. It is connected by control rod 181 with spring-buffer mechanism SB, which in turn is connected by rod 66 with the piston of power mechanism SM. The rod 67 which is primarily for the locking means is also connected with the piston of power mechanism SM. In the rod 67 are holes or notches, NP and RP, (Fig. 8) corresponding respectively with the normal position and the reverse position of the switch SW.

The power mechanism SM is shown in detail in Fig. 6, the same being a cross section through the length of the mechanism SM on a center line of the connecting rods 67 and 66. 252 is a piston in the cylinder of SM and is rigidly connected to rods 66 and 67.

60 Admission of air or fluid into the cylinder of SM for operating piston 252 is controlled by electromagnetic valves M1 and M2. These valves are identical in structure and action, therefore but one will be described.

65 Valve M1 consists of the following parts: 70

There is an electromagnet which comprises the magnetic core 218, the coil 220, and an enclosing shell. 212 is an armature for this electromagnet, held in an upright position by the tension in the spring 214. 222 is a valve closing 75

device which normally closes the port 228 at its lower end. The admission of air or fluid under pressure is from a source connected with opening 234; therefore this pressure against part 5 232 normally keeps port 228 closed. Normally chamber 236 is connected to exhaust port 224 through channels 230 and 228 and chamber 228. The connections to the electromagnet are conductors 24 and 25 which are also shown as a part 10 of the circuit in Fig. 3.

When valve device M1 is operated through the energizing of the electromagnet, armature 212 is attracted to core 218 against the tension of the spring 214. This causes the stem 216 which 15 is rigidly connected to armature 212 to bear down on valve device 222 closing the upper part of channel 228 and opening the lower part of said channel so that air or fluid under pressure is admitted from source opening 234 through channels 228 and 230 into chamber 236. The consequent pressure on piston 252 forces same to the other end of the cylinder, thus moving the switch SW from the normal to the reverse or open position. Chamber 237 is normally open to exhaust through port 225 via channels 231 and 229 25 and chamber 227 similarly as described for chamber 236.

The operation of the mechanism in moving the switch SW from reverse to normal or closed 30 position is similar to that already described for opening the switch in that air or fluid is admitted into chamber 237 through source opening 235 forcing the piston 252 back to its normal position at the other end of the cylinder.

35 After the switch points are moved to one or the other position, they must be locked in place, which locking is accomplished by the device SL. This is shown in detail in Fig. 7. 253 is a cylinder containing a piston 240 rigidly connected to a piston rod LP. Normally the piston 240 occupies the position indicated in cylinder 253. It is held in that position by the tension exerted from spring 239.

ML of Fig. 7 is an electromagnetic valve of 40 exactly the same structure as electromagnetic valve M1. When electromagnetic valve ML is operated, air or fluid is admitted from a source of supply under pressure connected with opening 250. Normally this pressure holds valve 248 to close channel 246 at its lower end. Normally 45 also chamber 251 is connected to exhaust port 245 through channels 249 and 246. Upon the operation of electromagnetic valve ML, valve 248 closes channel 246 at the top, and opens same at the bottom, so that the air or fluid under pressure 50 then flows into chamber 251 through channels 246 and 249. This pressure forces the piston 240 against the tension of the spring 239 withdrawing the lock plunger LP from the control rod 67.

Control rod 67 contains two holes or recesses 55 NP and RP respectively, corresponding with the normal and reverse positions of the switch SW, the same as indicated in Fig. 8. When the switch is moved to one position or the other, lock plunger LP locks the control rod 67 because of the force of the spring 239. The unlocking is always 60 done by the power means described.

The structure 197 Fig. 4 shelters the circuit controller contacts LC1, LC2, LC3 and LC4 of 65 Fig. 3. When the power means are applied to unlock the switch, the withdrawal of the plunger LP from the rod 67 operates the circuit controller contacts in device 197 to open contact LC1 and close contacts LC2, LC3 and LC4; these 70 circuit contacts are maintained in this operated condition during the period plunger LP is with-

drawn from control rod 67, even though the power may be cut off and the tension of spring 239 forces piston 240 back for LP to abut on control rod 67.

Referring to Fig. 9, ordinarily the switch points 5 have stroke of 5". Contacts C1, C3 and C5 are closed in the normal position of the switch, C1 opening about $\frac{1}{8}$, C3 about $\frac{1}{15}$ and C5 about $\frac{1}{5}$ of the stroke of the switch from normal to reverse position and closing at the same points in 10 the return of the switch from reverse to normal. Contacts C2, C4 and C6 are closed in the reverse, or open, position of the switch. They open and close in the movement of the switch from reverse to normal and normal to reverse respectively in a manner similar to that explained for contacts C1, C3 and C5.

Switch stand control.—Where the track switch is remotely controlled or where it may be controlled from an approaching train, it is desirable that an arrangement be made by which the switch may be moved by manual means and especially providing something occurs making the power means inoperative.

148 (Fig. 4) is a switch stand, normally disconnected from connecting rod 172 which is fastened to switch rod 68. Levers 150 and 171 are normally in the position shown. Lever 171 cannot be operated until lever 150 has been operated. Connecting between lever 150 and locking device 30 SL is rod 173 which ends in an arm 211 (Fig. 7) on the end of which is a roller 210. When lever 150 is thrown over to the opposite position, two things are accomplished: lock plunger LP is withdrawn from control rod 67 and lever 171 is connected to control rod 172. When lever 150 is thrown to the opposite position in withdrawing the lock plunger LP, roller 210 moves against part 35 238 which is rigidly connected with lock plunger LP, forcing same in the direction U, until the extreme limit of travel of roller 210 is reached, which is the position for arm 211 as indicated by dotted line 254. As the switch is unlocked, lever 171 is connected to control rod 172. Lever 171 may now be operated to open and close the 40 switch. It will be observed that the unlocking of control rod 67 by the switch stand lever 150 also causes the circuit controllers LC1, LC2, LC3 and LC4 to be operated the same as if the control rod 67 was unlocked by the power means 45 described.

The operation of the switch by the hand lever 171 also causes the circuit contacts of the controller SCC to be operated, the same as if the switch was operated by the power means.

Operation.—Assume a freight train 117 in the section C of a stretch of track (Fig. 1) proceeding in the direction indicated by the arrow DS, and that it is necessary for this train 117 to enter the siding to pass another train (not shown) 60 proceeding toward it. The latter train will keep the main line between the switches SW of the passing siding.

Communication between dispatcher and train.—The dispatcher operates his selective operating set SOS to energize selector relay YD closing contacts 180 and 183. This connects transformer WD to conductors D1 and D2. He then operates switch HS2—HS4 (Fig. 11) opening contact 378 and closing contacts 382 and 380. 70 This completes the circuit for the "Way-side transmitting signaling means" already described, including transformer WD. Interrupted electric current impulses from generator O2 are induced into intermediate circuit C through the trans- 75

former WD. Since inductor 115 is in inductive relation with conductors 103 and 105 of the intermediate circuit C, heretofore described, as the train proceeds through section C, the distinctive 5 electric impulses from generator O2 are reintroduced from intermediate circuit C into the circuit of inductor 115 which is normally closed on the receiving equipment of the set T and RC on the train. If there are two sets on the train, one 10 on the head end and one on the rear end, both receiving sets will receive the signaling impulses from generator O2. These impulses, on being received in inductor 115, are carried through transformer W5 to the receiver amplifying means, including first stage tube U1 and second stage tube U3, and then to the loud speaker or device LS1, which reproduces as a signal of distinctive character, these electric impulses which the dispatcher has sent out and intends to be received 15 20 on the train, notifying the attendants on the train that the dispatcher desires to communicate with them.

Through the means associated with the transmitting of the calling means, already described 25 under "Circuit for the wayside transmitting signaling means", the dispatcher is advised that the signaling impulses are actually produced by the generator O2.

Assume that the device LS1 receives the signaling code only; the train attendant, on hearing the dispatcher's call, removes receiver RE1 from switch arm SC1, which operation breaks contacts 361 and 373 and closes contacts 357 and 371, and operates switch SA1 to close contacts 335A, 303A 30 and 317. The attendant then talks into transmitter T1, energizing the "Circuits for transmitting communication from the train", advising the dispatcher that he is ready to receive orders and instructions. The voice currents in the inductor 115, are reintroduced into the conductors 103 40 and 105 of the intermediate circuit C, already described, energizing transformer WD. These voice current impulses pass through transformer WD into conductors D1 and D2 and the "Circuits for receiving in the wayside station", or dispatcher's office. It may be further assumed that in the meantime the dispatcher has operated switch arm SC2—SC4 to close contact 358 and 372. He 45 then receives the communication from the train in receiver RE2.

The attendant on the train after answering the dispatcher's call restores switch SA1 to its normal position. The dispatcher, on hearing the answer from the train, operates switch SA2 to close contacts 336A, 304A and 318 and talks into the transmitter T2 giving the attendant instructions for train 116 to enter the passing siding to allow the other train to pass. Communicating impulses for these instructions pass through the "Circuits for transmitting communications from the wayside", including transformer WD into the intermediate circuit C including conductors 103 and 105. Here they are re-induced into inductor 115 of receiving set T and RC and pass through "Circuits for receiving in a train station" to be reproduced in receiver RE1.

On receiving the instructions, the attendant on the train repeats them back to the dispatcher, and in so doing he first operates switch SA1 to close contact 335A, 303A and 317. The signals in repeating the instructions pass through the "Circuits for transmitting communications from the train", thence through the intermediate circuit of C and transformer WD to the roadside

system including conductors D1 and D2 and the "Circuits for receiving in the wayside station."

Signals S2 and S3 set at stop by dispatcher.—
In order to check against any misunderstanding of the instructions given a train, the dispatcher sets at stop, signals S2 and S3 which govern trains over the switch SW. The signal S2 will stop the train which is bound in the direction DN between the switches of the siding. The train 117 will be stopped at the signal S3 should it attempt to pass same before the switch SW is operated to divert 10 said train into the siding. The operation of signals S2 and S3 to cause them to indicate stop is brought about by the dispatcher operating the selective operating set SOS in his office to energize selector relay 11 which opens the contacts 56 and 49 in the circuits of signals S2 and S3 already described as "Circuit for signal S2", and "Circuit for signal S3".

Communication between conductor and engineman.—Assuming there are two communicating sets on the train, one in the locomotive on the head end and one in the caboose on the rear end, each as illustrated in Figs. 2 and 10, the train conductor in the caboose will now communicate 25 with the engineman in the locomotive to satisfy himself that the engineman has received and understands the orders and instructions of the dispatcher with regard to the train entering the siding.

In this communication the train conductor operates the switch HS1—HS3, to open contact 371 and close contacts 331 and 379 to connect generator O1 on inductor 115 as per "Circuits for the train transmitting signal means". In turn 35 the intermediate circuit C is energized by inductor 115 of the caboose through conductors 103 and 105. Inductor 115 on the forward end of the train picks up the electromagnetic impulses, from the communicating current circulating in the intermediate circuit C, through conductors 103 and 105 and these impulses are carried through the "Circuits for receiving in a train station", being received in device LS1 of receiving set T and RC on the locomotive.

In acknowledging the call the engineman may now operate switch HS1—HS3 of the set T and RC on the locomotive to close the circuit of generator O1, sending electric impulses back through the system as just described, to the caboose where 50 this answering signal is received by the device LS1 on the rear of the train.

Through the means associated with the transmitting of the calling means in the sets T and RC on each end of the train, already described, under "Circuits for the wayside transmitting signaling means", both the conductor in the caboose and the engineman in the locomotive cab are advised that the signaling impulses are actually produced by the respective generators O1 on each end of 60 the train.

On receiving the engineman's answering signal, the conductor operates switch SA1, to close contacts 335A, 303A and 317, and talks into transmitter T1. The electric impulses of this communication energize the "Circuits for transmitting communications from the train", and inductor 115 of the caboose energizes intermediate circuit C which re-induces the communicating impulses into the inductor 115 and the "Circuits 70 for receiving in a train station" of the set T and RC on the locomotive, the engineman in the meantime having closed contacts 357 and 371 of the switch arms SC1—SC3. In this communication it may be assumed the conductor has in- 75

structed the engineman to enter the siding at the switch SW, and to operate the switch SW as the train approaches the siding. Should the engineman reply to the conductor he will reply in a like manner as already described.

Operation of track switch SW.—On the train approaching the passing siding switch SW, either the dispatcher selectively closes contact 19 or the engineman reaches out from the cab and 10 grasps circuit controlling device HS, which is located along the track, and closes contact 19. This energizes relay R1, which remains energized because of the closing of its contact 7 in parallel with contact 19. The energizing of relay R1 also 15 closes contacts 15 and 26 and opens back contact 31.

With contact 15 closed, electromagnetic valve 20 ML is energized causing lock plunger LP to withdraw from control rod 67 and contacts LC2, LC3 and LC4 to close and contact LC1 to open.

The opening of contact LC1 opens the circuits of both signals S1 and S3. The closing of contacts LC2 and 26 in the circuit of magnetic valve ML results in this valve being energized so 25 that switch mechanism SM will function to reverse or open switch SW. Before switch SW has entirely completed its stroke, circuit controller C1 is open but since circuit contact LC4 is closed in parallel with C1, relay R1 continues 30 to remain energized so that the movement of switch SW is completed. As the switch moves from the normal or closed to the reverse or open position, circuit contact C5 opens so that magnetic valve ML becomes de-energized, but lock 35 plunger LP cannot enter control rod 67. When the switch SW is fully reversed and because ML is de-energized, the spring 239 (Fig. 7) forces lock plunger LP into the recess in control rod 67. With the control rod 67 becoming locked by 40 the plunger LP, circuit controllers LC1, LC2, LC3 and LC4 are restored to their normal condition. With the switch in the reverse position and locked, magnetic valve M1 and relay R1 become de-energized since contact C1 and LC4 45 for relay R1 are open, and contacts LC2 and 26 are open for magnet valve M1.

When the switch reaches the reverse position, contact C4 is closed, and when the switch is locked contact LC1 closes so that signal S1 50 clears for the train 117 to proceed over the switch and enter the passing siding. When the train is in track section F, relay TF is de-energized, opening contacts 34, 45, 60, 11, 23 and 72. Contact 45 opens the circuit for signals S1 55 and C3 and place signal S1 at stop. Contact 34 is open in the circuit of relay R2. Contact 60 is open in the circuit of signals S2 and S4. Contact 11 is open in the circuit of valve magnet ML. Contact 23 is open in the circuit of valve magnets 60 M1 and M2.

As the train proceeds the flanges of the wheels contact with bar FLB forcing it forward in the direction of the travel of the train, or position b (see Figs. 4 and 5) locking control rod 65 181 by plunger 65 entering recess of 181 and facing point lock casting 175. As the rear end of the train passes over the switch and the flanges of the wheels leave bar FLB, it returns to its normal condition through the force exerted 70 by springs 179 and 196 withdrawing lock plunger 65 from the facing point lock FPL. During the interval that the train is proceeding over the switch and the bar FLB has been in the position b, circuit controller 58 connected with rod 64 has 75 been open, but as soon as bar FLB returns to its

normal position this circuit controller is closed.

As the train proceeds into the siding, relay TG of track section G is de-energized, opening front contacts 52, 41, 13 and 14, and closing back contacts 28, 13 and 14. Contact 52 is open in 5 the circuit of signals S2 and S4. Contact 41 is open in the circuit of signals S1 and S3. Contact 28 is closed in the circuit of relay R2. While TF and TG are de-energized, signals S1, S2, S3 and S4 must remain at stop. 10

As the rear of the train leaves section F, relay TF again becomes energized, closing front contact 34 in the circuit of relay R2; front contact 45 in the circuit of signals S1 and S3; front contact 60 in the circuit of signals S2 and S4; 15 front contact 11 in the circuit of valve magnet ML, and front contact 23 in the circuit of valve magnets M1 and M2.

Since the rear end of the train is still in section G, relay TG is still de-energized with contact 52 open in the circuits of signals S2 and S4, and contact 41 open in the circuits of signals S1 and S3. As contact 28 is closed on its back point, relay R2 is now energized by way of back contact 31 closed, front contact 34 closed, and contact C2 closed. With relay R2 energized, front contacts 39 and 19 are closed, and back contact 2 is opened. The closing of front contact 19 energizes the valve magnet ML by way of contact C6 closed, while the switch is reversed, and contact 11 closed. With valve magnet ML energized, lock plunger LP is withdrawn from control rod 67, closing contacts LC2, LC3 and LC4, and opening contact LC1. The closing of contact LC2 with front contact 39 closed, energizes valve 35 magnet M2, which causes air to enter chamber 237 of the cylinder of SM, closing the switch SW. As the switch closes, or returns to normal, contacts of circuit controller SCC are made and broken in the following order: C4 and C6 are 40 broken, C1 made, C2 broken, C5 and C3 made. When contact C6 is open, magnetic valve ML is de-energized, but upon the switch again reaching full normal position, lock plunger LP is forced into the recess of control rod 67 by spring 45 239. This causes contacts LC1, LC2, LC3 and LC4 to assume their normal position, so that valve magnet M2 is de-energized, and relay R2 is de-energized. With contact LC1 closed and contact C3 closed, signal S3 is in a condition to 50 indicate proceed, except for contacts 49 and 41 still being open and the train in the block on the main line between switches SW.

As the rear end of the train leaves track section G relay TG becomes energized, restoring its 55 various contacts to their normal positions.

Communication between conductor and engineman and dispatcher as train approaches and enters siding.—When the train is in section D, transformer WD is automatically disconnected 60 from the intermediate circuit. While the train is passing through section D, any communication between conductor and engineman or between train and dispatcher, must be carried on through the combined intermediate circuits of sections C 65 and E already described, and transformer WF. As the rear end of the train clears section D, moving in direction DS, the train is wholly within intermediate circuit E, and any communications taking place either between rear end and head 70 end or train and dispatcher will be by way of conductors 107 and 109 and transformer WF.

While the train is in section F transformer coil WF is eliminated from the communication circuit. During this period any communication be- 75

tween conductor and engineman or between train and dispatcher must be through the combined intermediate circuits E and I and a transformer WK (not shown) at the far end (not shown) of intermediate circuit I.

- As the train proceeds into the siding and section G, but also is still in section F, any communication taking place between conductor and engineman or train and conductor, will be by way of the combined intermediate circuits E and H and transformer WF. This same channel for communication exists when the train is in section G, and has cleared section F restoring intermediate circuit I to its normal condition.
- When the rear end of the train passes over the switch SW, the conductor will so advise the engineman that the train may be stopped to clear the fouling point with the main line, providing a stop of the train is necessary.
- When the train is wholly within the intermediate circuit H, the conductor will report the presence of the train on the siding to the dispatcher, the channel of communication being by way of transformer WG, which is automatically connected to the dispatcher's line by the train being in the circuit of relay TH. This information from the conductor of the train on the siding will be authority for the dispatcher to operate selector 17 to close contacts 56 and 49 that signal S2 may clear for the train on the main line to proceed in direction DN, and for signal S3 to clear as soon as the train on the main line has passed by it and out of its block.

Train on main line proceeds.—As has heretofore been explained, signals S2 and S4 are controlled by contact 58. Should bar FLB fail to return to its normal position unlocking control rod 181, signals S2 and S4 would not clear. As the train which has kept the main line between the switches SW proceeds in the direction DN, its flanges and wheels come in contact with bar FLB, forcing it forward in the direction DN of the train, or position a, (Fig. 5), withdrawing the lock plunger 65 further away from control rod 181. Should the switch SW be in the reverse position, the train on the main line could trail through the points without damage resulting. Further a train on the siding may come out on the main line trailing through the switch, which is in its normal position, without damage resulting.

Communication between conductor and engineman and dispatcher as train approaches and enters siding, Fig. 12.—When the train is in section F1, the normally separate intermediate circuits E1 and H1—II are transposedly connected together in one combined intermediate circuit or communicating zone. The inductor 115 on the train is located to be in inductive, or communicative relationship with conductors 400, 403, 405 and 407 on the track as the train progresses, so that any communicating signals passing between conductor and engineman or either of these and the dispatcher must be by way of these conductors.

While the train is in section F1 transformer WFI is eliminated from the intermediate circuit by reason of back contact 401 being open. During this time conversation between the train and the dispatcher is by way of transformer WK1 and conductors D1 and D2.

The method of signaling, transmitting and receiving communications,—as to the equipment on the train and in the dispatcher's office, is the same as heretofore explained.

Communication between conductor and engineman and dispatcher and between attendants on two trains and/or between the attendants on one or both trains and the dispatcher while in intermediate circuit H1—II, Fig. 12.—While a train is in siding, inductors 115 of the train are in inductive, or communicative relationship with the conductors 403 and 405 of the intermediate circuit H1—II. The same is true for a train on the main line. The dispatcher is in communicative relationship with intermediate circuit H1—II through transformer WK1. Any communication passing between rear end and head end of either train, or between the two trains, or between either or both trains and the dispatcher must be through intermediate circuit H1—II.

The procedure in signaling, transmitting and receiving communications between the rear end and head end of a train, and between the dispatcher and a train has heretofore been explained. This procedure between two trains is identical with that of carrying on communication between the rear and head ends of a train. It is readily seen how the parties on the two trains and the dispatcher may communicate together. Such a form of communication will often be desirable in a system for operating trains where the dispatcher desires to give instructions to the two trains in regard to their further procedure and both trains are mutually concerned.

A train on the siding proceeding to the main line.—As a further detail in the operation of train, assume a train in the siding bound in the direction DN waiting for a train on the main line and that this latter train has just passed through. After the dispatcher instructed the train bound in the direction DN to enter the siding, he operated selector relay 18 to open contact 71 to place signal S4 at stop as a precaution against the train leaving the siding until proper for it to do so. Now that the main line train has passed, the dispatcher operates selector relay 18 again to close contact 71 that signal S4 may clear for the train to leave the siding. In case further orders are necessary, the same may be issued to the train on the siding before signal S4 clears. The procedure in issuing orders to a train has already been described. As arranged in Fig. 3, the circuit for signal S4 is not dependent upon the position of the switch SW. It is, however, governed by the position of the approach locking means. If the fac-
ing point lock FPL is unlocked, contact 58 in the circuit of signal S4 is closed and, with its block clear, signal S4 will clear. The switch SW may be set for train movements along the main line, but the train on the siding may proceed trailing through the points of switch SW which is permissible because of the spring and buffer connection SB joining the mechanism SM to the control rod 181 for the switch. As the train proceeds through the switch, the wheels contact with bar FLB operating same to keep switch points unlocked that the latter will be free to be moved over as the wheel flanges force them over. When the train has cleared the switch, points 190 and 191 return slowly to their normal position because of the spring and buffer action.

Operation of switch SW by dual switch stand.—In the case of a train desiring to enter the siding and it should be found impossible to operate the switch SW by the power means provided, as illustrated in Fig. 3, an attendant of the train may operate the switch with the dual switch stand. Lever 150 is first thrown over, which operation causes lock plunger LP to be withdrawn from rod 75

67 and lever 171 to be connected to switch rod 172. Lever 171 is next thrown over, which operation reverses switch SW. The withdrawing of plunger LP from rod 67 causes circuit contact 5 LC1 to open in the circuits of signals S1 and S3, holding these signals in the stop position. The train may now proceed into the siding under the usual hand signal of the trainman and the procedure prescribed by the railroads for making 10 train movements against stop signals. As the train proceeds, relay TF is de-energized, facing point lock FPL is operated to lock the switch, relay TG is de-energized and relay TH is de-energized the same as would be the case if the train 15 entered the siding after the switch had been operated by the power means provided. After the train has entered the siding the attendant of the train returns the switch SW to its normal position by restoring levers 171 and 150 respectively to 20 their normal positions.

General.—While my disclosure shows amplification of transmission as well as of reception of communicating signals, I do not wish to be confined strictly to such use, nor to the stages and 25 form of amplification illustrated. For some of the features and under some conditions, amplification of the signals on transmission only is necessary. Under other conditions amplification of the signals when received is sufficient. Generally, amplification of the signals at transmission is desirable in order to put all the power necessary into the intermediate circuit to raise the 30 energy of the communicated signals above the energy of foreign induced currents that cause 35 bothersome noises in the receiver. Amplification of received signals also amplifies the energy of noise currents which may be in the circuits between the transmitting and receiving points, and not eliminated.

40 Should the parties concerned in communicating between the two ends of a train or between the train and the wayside station so desire, a code of signals for communication by the signaling means described may be used, instead of always 45 resorting to telephoned communications. This is particularly true for communicating between conductor and engineman where oftentimes a code of signals for certain brief messages would be less trouble than telephone conversation.

50 Contact 19 for reversing switch SW may be operated by manual means from the ground or the locomotive or by mechanical means carried on the locomotive; or it may be closed inductively as disclosed in my co-pending application Serial 55 #198,824; or it may be closed by a selector under the control of the dispatcher's selective system. For some railroads, this latter method for closing contact 19 in the operation of the switch SW is preferable for all switches, or part of the 60 switches, in the stretch where the system described is installed.

Electromagnetic valve ML may be controlled by a contact 11 operated by bar 64, closed when bar 64 is in normal position and open otherwise, 65 instead of a contact 11 operated by track relay TF. Such an arrangement would also make impossible the operation of power mechanism SL to withdraw lock plunger LP while a train is on the switch SW. Similarly electromagnetic valves M1 and M2 may be likewise controlled; i. e., instead 70 of contact 23 being controlled by relay TF it may be controlled to be closed when bar 64 is normal but open otherwise. With such an arrangement neither M1 or M2 could be operated while a train is on the switch SW. Since valve magnet 75

ML is controlled by a contact 11 operated by either relay TF or bar 64 and valve magnets M1 and M2 are controlled through LC2 by the operation of magnet ML, contact 23 for the controlling of magnets M1 and M2 is but an extra 5 precaution.

Relay R2 may also be operated by a contact 34 controlled from bar 64 instead of from relay TF, such contact 34 being closed with bar 64 in normal position but open otherwise. Such an 10 arrangement would prevent switch SW being operated on the closure of contact 28 to energize relay R2 with a train in contact with bar FLB to lock the switch at FPL.

In the invention disclosed in this application 15 I have described the use of a conductor located on the track as part of the closed metallic intermediate circuit, for transmitting and receiving communicating signals, particularly as this construction lends itself readily to minimizing and 20 eliminating the effects of any foreign electrical currents which would otherwise cause bothersome noise disturbances.

In my co-pending application, Serial #227,932, 25 I use the track rails as a part of the closed metallic intermediate circuit for transmitting and receiving the communicating signals, such an arrangement being desirable particularly from the standpoint of safety, the cost of construction and maintenance, and convenience in 30 the arrangement of means for co-operation between train carried and wayside devices.

It is now apparent that in applying this system of communication to some stretches of railroad both types of intermediate circuits may be 35 used; in some territories the track rails and in other territories of the same stretch the conductor located on the track may be the medium for transmitting and receiving the communicating signals passed between the train and the 40 wayside and between the two ends of the trains.

The inductor on the train may be located to co-operate in transmitting and receiving with either of said types of intermediate circuit.

What I claim as new is: 45

1. In a system adapted for communicating between the two ends of a railway train and/or between a railway train and a wayside station, in combination, transmitting and receiving means on each end of the train, transmitting and receiving means in the wayside station, an intermediate circuit composed of transposed conductors connecting together said train end means and means in said circuit adapted to be operated to connect said train end means with said wayside station means, the arrangement being such that the communication characteristics of said intermediate circuit are constant, and means amplifying the communicating signals as transmitted between said train ends and/or between 55 said train ends and said wayside station.

2. In a system for communicating between the two ends of a railway train on a stretch of track and/or between said train and a wayside station, an intermediate circuit associated with the 65 track rails of said stretch, said intermediate circuit being comprised of conductors and a transformer in circuit therewith, said conductors being connected in transposed relationship at intervals under control of said train.

3. In a system for communication between the two ends of a railway train and/or between the railway train and a wayside station, the combination comprising a transmitting and receiving set on each end of said train and in said 70 75

- wayside station, a series of intermediate circuits, each connecting between said sets as the train moves over the railroad, and means operative to connect adjacent circuits of said series together 5 in transposed relation.
4. In a system for communicating between the two ends of a railway train on a stretch of track and/or between the railway train and a wayside station, an intermediate circuit comprising transposed conductors along said stretch, a transformer in circuit with said conductors, and means at the ends of said stretch connecting the conductors together, said means being adaptable to join said circuit to an adjacent similar intermediate circuit and to eliminate the transformer from said first named circuit while the two intermediate circuits are joined.
5. In a system for communication between the two ends of a railway train and/or between the 20 railway train and a wayside station, a signalling means on each train end and in the wayside station, said signalling means including a source of energy of a prescribed frequency for said train ends and said station to give a certain signal 25 when transmitted from said train ends and a different signal when transmitted from said station, an intermediate circuit connecting between said train ends and said station in electrical relation with all of said means, and means amplifying the signals transmitted between said train ends and said station.
6. In a system for communicating between the two ends of a railway train and/or between two railway trains, a stretch of parallel tracks for 30 trains, a transmitting and receiving communicating set on each end of said trains, and an intermediate circuit in inductive relation with said train sets, said intermediate circuit comprising a conductor on the wayside of each of 35 said tracks and circuit controlling means at the ends of said stretch connecting said conductors together.
7. In a system for communication between the two ends of a railway train and/or between the 40 railway train and a wayside station, a signalling means on each train end and in said station comprising, a source of energy of a prescribed frequency, a circuit means for transmitting the energy impulses from said source, a condenser 45 for making said circuit resonant or nearly so to said frequency, and an auxiliary circuit connected to said energy source including a device responsive to the frequency of said current source operative to indicate when said source is operating in said transmitting circuit.
8. In a system for communicating between the two ends of a railway train and/or between the railway train and a wayside station, a transmitting and receiving set comprising, a normally 50 open transmitting circuit, a normally closed receiving circuit, means in said transmitting circuit for sending out calling signals and voice signals and for amplifying only said transmitted voice signals, means in said receiving circuit for receiving calling signals and voice signals and for amplifying the same, and devices responsive to said received amplified calling signals and voice signals.
9. In a system for communicating between the two ends of a railway train on a stretch of track and/or between the railway train and a wayside station, an intermediate circuit comprising, transposed conductors along said stretch, and means 60 connecting the ends of said conductors together,
- said means being adaptable to join said circuit to another intermediate circuit of said stretch.
10. In a system for communicating between the two ends of a railway train and/or between the railway train and a wayside station, an intermediate circuit in the track wayside system of a stretch of parallel tracks for trains, comprising a conductor on the wayside of one of said tracks, a conductor on the wayside of the other of said tracks, a transformer at one end of said stretch 10 in series with said conductors, and means operative by passing trains connecting said conductors together at each end of said stretch.
11. In a system for communicating between the two ends of a railway train and/or between the 15 railway train and a wayside station, a stretch of parallel tracks for trains, a transmitting and receiving communicating set on each train end and in said wayside station, and an intermediate circuit in inductive relation with said train sets 20 and adapted to be connected to said wayside station, said intermediate circuit comprising a conductor on the wayside of each of said tracks, means at the ends of said stretch for connecting said conductors together and a transformer connecting the wayside station set in circuit with said conductors.
12. In a train operating system means for communicating between the two ends of a railway train and between either or both ends of the 25 railway train and a wayside station, a stretch of track for the train, a telephone line and selective system for said stretch connecting with a transmitting and receiving communicating set in said wayside station, a series of electrically independent 30 intermediate circuits for said stretch each adapted to be selectively connected with said telephone line by said selective system, and a transmitting and receiving communicating set on each train end in electrical relation with said 35 intermediate circuits for normally maintaining 40 communication between said train ends.
13. In a means for communicating between the rear end and head end of a railway train on a 45 stretch of track, a wayside system comprising, a plurality of conductors generally parallel to said track and connected together at intervals to form a series of intermediate circuits, and means in said circuits controlled by the train transposing 50 said conductors with reference to each other and to the rails in said track.
14. In a means for communicating between the rear end and the head end of a railway train on a stretch of track, a wayside system comprising, a series of pairs of conductors, and operable means 55 associated with said track connecting said pairs at each end to form a series of electrically separate and independent circuits, said means when operated being adapted to connect together adjacent circuits of said series.
15. In a means for communicating between a railway train on a stretch of track and a wayside station, a wayside system comprising, a wayside communicating circuit connecting to the wayside station, conductors along said stretch 65 transposed at intervals, means operatively associated with said stretch connecting said conductors together to form an intermediate circuit including said transpositions, and means operative from said wayside station adapted to connect the communicating circuit with said intermediate circuit.
16. In a means for communicating between a railway train on a stretch of track and a wayside station, a wayside system comprising, a wayside communicating circuit connecting to the way- 70 75

- side station, a series of pairs of conductors along said stretch, means associated with said stretch normally connecting said pairs at each end to form a series of electrically independent circuits, 5 and means adapted to connect the communicating circuit with each of said series of independent circuits, some of said means being governed from said wayside station and other of said means being governed from said track.
- 10 17. In a system for communicating between a wayside station and a railway train and/or between the two ends of a railway train, in combination, transmitting and receiving means on each end of the train, an inductor and circuit in each 15 of said train means, a closed conductive wayside circuit in a constant inductive relation with said inductors, a wayside transmitting and receiving means, means associated with said wayside circuit and controlled from the wayside station 20 adapted to connect said wayside transmitting and receiving means with said wayside circuit, and means amplifying the communicating signals when transmitted from and received on said train ends.
- 25 18. In a system for communicating between a vehicle operating in a district and a wayside station, a communication set on the vehicle including a transmitting and receiving means and an amplifier of communication signals, a wayside 30 station communicating set including transmitting and receiving means, a series of separate and independent wayside mediums for carrying communication impulses, each adapted to be in communicative relation with the vehicle communication set, and means controlled from the wayside station adapted to communicatively connect the wayside station communication set with any one or more of said mediums.
- 35 19. In a system for communicating between a wayside station and a vehicle in a stretch of track, a wayside system comprising, a series of intermediate circuits for said stretch, each of the series being a circuit separate and distinct from the other circuits of said series and composed of 40 transposed conductors, a wayside communicating circuit connecting to the wayside station, and means adapted to place the wayside communicating circuit in communicative relation with any one or several of said intermediate circuits.
- 45 20. In a system for communicating between the two ends of a railway train in a stretch of track, a wayside system comprising, a series of intermediate circuits for the stretch, each of the series being a circuit normally separate and distinct from the other circuits of said series, and means operative to transform adjacent circuits of said series into one enlarged intermediate circuit also separate and distinct from the other adjacent circuits of the series.
- 50 21. In a system for operating trains over a stretch of track under the control of a dispatcher, a passing siding in said stretch, a train on said passing siding bound in a certain direction, a moving train in said stretch bound toward said passing siding, signals at said passing siding governing train movements over the switches of said siding and a circuit for each of said signals, communicating means on said trains and in the dispatcher's office, normally electrically isolated 55 intermediate circuits for said stretch, including the passing siding, in communicative relation with said train communicating means and adapted to be placed in communicative relation with the dispatcher's communicating means, 60 track circuits controlling both said signal cir- 5
- cuits and said intermediate circuits, and selective means operative by the dispatcher for connecting the dispatcher's office communicating means with said intermediate circuits and for controlling the circuits of said signals, the arrangement being such that after the dispatcher has communicated with the trains and given them instructions, he may operate said signals as a check on his instructions to hold the train on the siding and to permit the moving train to 10 proceed without stopping.
22. In a system for operating a train over a stretch of track under the control of a dispatcher, a main line and a siding in said stretch adapted to be connected together by a switch, signals for 15 governing the train over the switch, means for exchanging communications between the train and the dispatcher, selectively operated means controlled by the dispatcher controlling the indications of said signals and said exchange of communications while the train is approaching said siding, and means controlled by the train controlling said exchange of communications while the train is on said siding. 20
23. In a system under the supervision of a dispatcher for operating railway trains, a stretch of track for trains including a main line and a siding adapted to be connected together by a switch, a normally clear signal S4 governing trains over the switch from the siding to the main line, 25 a normally clear signal S3 governing trains over the switch along the main line in a direction facing the switch, a normally clear signal S2 governing trains over the switch along the main line in a direction trailing the switch, a circuit in communicative relation with trains occupying said stretch of track, a dispatcher's line, and means selectively controlled by the dispatcher over said line for controlling the indications of said signals and for connecting said circuit to the line. 30 40
24. In a system for operating railway trains, a stretch of track for trains, operating under the supervision of a dispatcher, including a main line and a siding adapted to be connected together by a switch, means for exclusive communication between any one of said trains and the dispatcher, said communications being receivable on and transmittable from said train, a power mechanism for operating said switch to open and close the same, means selectively controlled by the dispatcher controlling said communication means, that the dispatcher may instruct said one train to enter the siding, and controlling said power mechanism to open said switch, that the train may enter the siding, and means controlled by said train, effective after passing over the switch, controlling said power mechanism to close said switch and controlling said communication means that the train may advise the dispatcher of its arrival on said siding. 35 50 55 60
25. In a system for communication between a plurality of railway trains in a stretch of track and a wayside station, means on each train for transmitting a signal and receiving a distinctively different signal, means in the wayside station for receiving said signal transmitted from the train and for transmitting said distinctively different signal to the train, and means associated with said station for selectively placing the transmitting and receiving means of said station in operative relationship with the transmitting and receiving means on one or more than one of said trains. 65 70
26. In a system for communication between the two ends of a railway train and/or between 75

- the railway train and a wayside station, in combination, a communication set on each train end and in said station, including a source of energy a circuit means for carrying energy originating 5 in said source, and an auxiliary means associated with said energy source adapted to indicate when said source is active in said circuit means, wayside means communicatively connecting between said train sets and other means associated with 10 said wayside means adapted to be controlled either by said train or from said wayside station placing said train sets in communicative relation with said station set.
27. In a system for communicating between a railway train in a stretch of track and a wayside station, a series of sections in said stretch each with an intermediate circuit, a wayside communication station adapted to be communicatively connected with one, or more than one, of 15 said intermediate circuits, means associated with said one, or more than one, of said intermediate circuits creating therein certain electric effects, and receivers on said train and in said station responsive to said effects indicating on said train 20 when it enters the section for, and in said station when it is communicatively connected to, said one, or more than one, of said intermediate 25 circuits.
28. In a system for communicating between two trains in a section of parallel track railroad and between either or both of said trains and a wayside station, a communication set on each train and in the wayside station, an intermediate circuit associated with said parallel tracks in continuous communicative relation with each of said 30 train sets, and means operable, either from said station or by said trains, connecting said station in communicative relation with said intermediate circuit, said intermediate circuit for the condition 35 of continuous communicative relation between said train sets being thereby unchanged.
29. In a system of communication for railway trains, a stretch of track for trains, sections in said stretch, each with an electrically isolated intermediate circuit, and means controlled from a wayside station for placing the circuits for sections remote from each other in communicative relation.
30. In a system of communication for railway trains, a stretch of track for trains divided into sections, an electrically isolated intermediate circuit for each section, a train in each of a plurality of said sections, communication means on each train end in electrical relation with the intermediate circuit for the section occupied by the train that communication may be carried on between the ends of each train, and means controlled from a wayside station adapted to connect the intermediate circuits for sections remote 55 from each other that the trains in said remote sections may also communicate with each other.
31. In a system for operating a train over a stretch of track under the control of a dispatcher, in combination, a main line and a siding in said stretch adapted to be connected together by a switch, and a system for communication between said train and said dispatcher, comprising a communication station on the train, a communication station on the wayside, and means connecting said train and said station in communicative relation controlled by the dispatcher as the train approaches said switch and controlled by the train after the train has passed over the switch.
32. In a system for regulating the movement 5 of trains over a stretch of railway track including a track switch connecting two separate lines of track in which the position of the switch is controlled from a central point over a control circuit, a communication circuit associated with the stretch of track and disposed so as to electrically co-operate with telephone apparatus carried by trains moving through the stretch, means controlled from the central point over the control circuit for connecting said two circuits together to establish a telephonic connection between said central point and a train approaching the track switch, and means controlled by the train after passing the track switch for connecting said two circuits to establish a telephonic connection between the central point and the train.
33. In a system for regulating the movement of trains over a stretch of railroad track including a main line and a siding connected by a track switch in which the position of the track switch is controlled from a central point over a control circuit comprising two conductors, a plurality of intermediate circuits associated with the stretch of track and disposed so as to electrically co-operate with telephone apparatus carried by trains moving through the stretch, means controlled by a train for connecting adjoining intermediate circuits in transposed relationship as a single intermediate circuit to provide a communication link between telephone sets at two points on the train, and means controlled from said central point over said control circuit for connecting said last intermediate circuit to the control circuit to provide a communication link between the train carried telephone sets and a telephone set at the central point.
34. In a telephone system for communicating between a moving train and a wayside point, an intermediate circuit electrically connecting the telephone set on the train with the telephone set at the wayside point, and means for automatically inserting transpositions in said circuit as the train moves along the track.
35. A trackway system of circuits for interconnecting train telephone stations comprising, a sectionalized stretch of track for trains, a first and a second conductor located generally parallel to the rails of each track section, said first conductor being disposed for an initial part of its length between the track rails and for the remainder of its length at a distance from the track rails, said second conductor being disposed for an initial part of its length at a distance from the track rails and for the remainder of its length between the track rails, and a switching device associated with each track section for temporarily connecting the first and second conductors of the associated track section with the second and first conductors, respectively, of the adjoining track section.
36. A trackway system of circuits for interconnecting train telephone stations comprising, a sectionalized stretch of track for trains, a first and a second conductor located generally parallel to the rails of each track section, said first conductor being disposed for an initial part of its length between the track rails and for the remainder of its length at a distance from the track rails, said second conductor being disposed for an initial part of its length at a distance from the track rails and for the remainder of its length between the track rails, a transformer, and a switching device associated with each track section for connecting the first and second conductors of the associated track section to a winding of said transformer and for connecting the first

and second conductors of the adjoining track section together.

37. A trackway system of circuits for inter-connecting train telephone sets comprising the combination with two parallel tracks for trains, of a first conductor located for an initial part of its length between the rails of one track and for the remainder of its length between the rails of the other track, a second conductor located for an initial part of its length between the rails of said other track and for the remainder of its length between the rails of said one track, and a train controlled switching device for temporarily connecting said conductors together.
38. In a train communication system, a stretch of railway track, a plurality of sections in said stretch, an electrically isolated loop circuit for each section, a track circuit in one section, means associated with said track circuit adapted to extend the loop circuit for said one section to include the loop circuit for the adjoining section, a train in said one section, and transmitting means on said train including a train carried transmitting circuit in inductive relation through an air gap with the loop circuit for said one section to induce communication current in said loop circuit to flow only in said loop circuit while

the train occupies said one section outside the limits of said track circuit and to induce communication currents in the extended loop circuit to flow in said extended loop circuit only while the train occupies said one section and is wholly or partially within the limits of said track circuit.

39. In a train telephone system, a stretch of sectionalized railway, a plurality of normally closed electrically nonrelated loop circuits, one for each section, a train in each of adjoining sections, a telephone set on each end of each train including train carried circuits, for transmitting and receiving the telephone signal currents, in inductive relation through an air gap with the loop circuit for the section occupied by the train, said currents when transmitted from one train end being received only on the other end of the same train, a track circuit in each of said sections, and means controlled by the track circuit when said track circuit for one of said sections is occupied by the train in that section connecting together the loop circuits for the adjoining sections so that the telephone signal currents transmitted from one train end are received on the other end of the same train and on one end of the train which is in the adjoining section.

and second conductors of the adjoining track section together.

37. A trackway system of circuits for inter-connecting train telephone sets comprising the combination with two parallel tracks for trains, of a first conductor located for an initial part of its length between the rails of one track and for the remainder of its length between the rails of the other track, a second conductor located for an initial part of its length between the rails of said other track and for the remainder of its length between the rails of said one track, and a train controlled switching device for temporarily connecting said conductors together.
38. In a train communication system, a stretch of railway track, a plurality of sections in said stretch, an electrically isolated loop circuit for each section, a track circuit in one section, means associated with said track circuit adapted to extend the loop circuit for said one section to include the loop circuit for the adjoining section, a train in said one section, and transmitting means on said train including a train carried transmitting circuit in inductive relation through an air gap with the loop circuit for said one section to induce communication current in said loop circuit to flow only in said loop circuit while

the train occupies said one section outside the limits of said track circuit and to induce communication currents in the extended loop circuit to flow in said extended loop circuit only while the train occupies said one section and is wholly or partially within the limits of said track circuit.

39. In a train telephone system, a stretch of sectionalized railway, a plurality of normally closed electrically nonrelated loop circuits, one for each section, a train in each of adjoining sections, a telephone set on each end of each train including train carried circuits, for transmitting and receiving the telephone signal currents, in inductive relation through an air gap with the loop circuit for the section occupied by the train, said currents when transmitted from one train end being received only on the other end of the same train, a track circuit in each of said sections, and means controlled by the track circuit when said track circuit for one of said sections is occupied by the train in that section connecting together the loop circuits for the adjoining sections so that the telephone signal currents transmitted from one train end are received on the other end of the same train and on one end of the train which is in the adjoining section.
